UNITED STATES PATENT OFFICE.

HERMAN W. KOERNER, OF WAUWATOSA, WISCONSIN.

METALLIC SHINGLE.

1,204,885.

Specification of Letters Patent.

Patented Nov. 14, 1916.

Application filed April 20, 1914. Serial No. 833,017.

To all whom it may concern:

Be it known that I, HERMAN W. KOERNER, a citizen of the United States, residing at the town of Wauwatosa, county of Milwaukee, and State of Wisconsin, have invented new and useful Improvements in Metallic Shingles, of which the following is a specification.

My invention relates to improvements in roof coverings.

The object of my invention is to provide a practical and inexpensive substitute for the ordinary wooden shingles heretofore used, this being accomplished by designing a metallic shingle of a form adapted to interlock in water-tight relation with like shingles with a minimum over-lap.

In the drawings—Figure 1 is a plan view of a fragment of a roof, showing a set of shingles embodying my invention applied thereto. Fig. 2 is a sectional view of a roof covered with shingles embodying my invention and showing the ridge or apex member. Fig. 3 is a detail view of the blank 25 from which the shingles A are made with the folding lines dotted. Fig. 4 is a sectional view taken on line $\alpha-\alpha$ of Fig. 1. Fig. 5 is a plan view of a modified form of shingle embodying my invention. Fig. 6 is a detail sectional view, drawn to a transverse plane indicating two shingles of the type shown in Fig. 5 in interlocking relation.

Like parts are identified by the same reference characters throughout the several views.

Each of my improved shingles comprises a sheet metal member A, which may be slightly arched as shown in Fig. 2, or flat as shown in Fig. 4, where it is designated by the reference character A'. The member A is preferably diamond shaped or hexagonal in form, said member as illustrated in Fig. 1 being diamond shaped, while in Fig. 45 it is substantially hexagonal. Along two margins which diverge from one corner, it is provided with flanges which are reversely folded along two parallel lines α, α' , to form an inturned portion B underneath the margin of the member A, and an outwardly extending portion C which projects from underneath the member B as clearly shown in Fig. 2. The outer margin of the portion C extends beyond the margin of the member A and this marginal portion of the member C

constitutes the nail receiving member of the shingle. It is therefore flat in form and adapted to rest upon a roof board D, to which it may be secured by nails E. These shingles may be formed of galvanized iron or other non-corrosive durable material, and for the purpose of securing additional durability or improving their appearance, they may be provided with a coating of any suitable material. For example, they may be 60 enameled, japanned, shellacked, painted, varnished, sanded or covered with vitrified substances baked thereon, and colored to suit the desire of the purchaser. Enamelled shingles will be preferably used.

The other two margins F and G of the member A are straight edged and are adapted to enter the groove formed by the members B and C of an adjacent shingle. The shingles are preferably laid as illustrated in Fig. 1, with one set of opposing corners extending in straight lines up the surface of the roof at right angles to the ridge, and the other set of opposing corners in lines parallel to the ridge, thus sub-dividing the roof into sections which are substantially diamond shaped.

A substantially semi-cylindrical member H, preferably of the same material as the shingles is employed to cover the ridge. 85 Each margin of this member is folded inwardly along the line h and folded or doubled upon itself at h' , from which fold it extends outwardly at an angle conforming to the pitch of the roof and constitutes 90 a connecting flange I adapted to be secured to the roof boards by nails i. In covering the roof with my improved shingle, this member H is first secured in a position covering the ridge with the flanges I nailed to 95 the roof at each side of the ridge. The upper tier of shingles is then applied. The shingles in the upper tier are triangular in form, each comprising a member A'' corresponding to the lower half of the members 100 A, the side margins of the triangular member A'' being provided with the reversely bent marginal portions B, C. The upper margins of the triangular shingles A'' are adapted to enter the groove formed by the 105 reversely bent marginal portions of the member H.

After the shingles A'' are in position, they are nailed to the roof boards D, the nails E passing through the exposed portions of the 110

members C. The second tier of shingles A will then be applied with their upper portions occupying the angular spaces between the downwardly extending apexes of the shingles A'' and their upwardly converging side margins entering the grooves between the members B and C of the reversely bent side margins of the shingles A''. The second tier of shingles will then be nailed 10 to the roof boards, the nails E passing through the exposed portions of the member C along the downwardly converging margins of the respective shingles, after which the third tier of shingles will be applied 15 with their upper half portions occupying the angles between the downwardly extending points of the second tier of shingles, the straight edge margins of the shingles in the third tier entering the interlocking grooves 20 in the lower margins of those of the second tier.

It will be observed in Fig. 3 that the blank from which the shingles A are formed is cut in such a manner that the lower ends C' 25 of the members C do not extend to the point of the member A, but terminate at the point where the channels between the members B and C meet. This avoids unnecessary over-lapping and interference at the apex 30 points.

Referring to Figs. 5 and 6, it will be observed that the structure is similar to that of the shingles shown in Figs. 1 and 2, except that the members A³ are hexagonal in 35 form. These members have upwardly and downwardly extending apexes as in the other views, but they also have sides which extend substantially at right angles to the ridge. One of these side margins has an angular 40 upwardly projecting portion L, which is elbowed at 1 and turned abruptly downwardly substantially in a vertical plane forming a wall M. The opposing margin of the member A³ is provided with a hook shaped 45 flange N, adapted to engage in the angle between the members L and N of an adjacent shingle in the tier, thus forming a watertight joint. In laying these shingles, the first tier will be laid at the ridge as de-

scribed with reference to the shingle illustrated in the other views.

I claim—

1. A sheet metal shingle having a diamond shaped body portion adapted to be disposed upon the roof with two of its corners in a line substantially parallel with the ridge and with the portion adjacent to the upper corner substantially flat, said body portion having flanges along its downwardly converging side margins which are reversely folded to form channels along said margins underneath the exposed surface of the body of the shingle, said flanges terminating at points sufficiently above the lower corner of the body portion to permit the insertion of meeting lateral corners on adjacent shingles under the lower corner of said body portion with one side margin of each adjacent shingle engaged in one of said channels, substantially as described. 70

2. A sheet metal shingle having a diamond shaped body portion adapted to be disposed upon the roof with two of its corners in a line substantially parallel with the ridge and with the portion adjacent to the upper corner substantially flat, said body portion having flanges along its downwardly converging side margins which are reversely folded to form channels along said margins underneath the exposed surface of 80 the body of the shingle, said flanges terminating at points sufficiently above the lower corner of the body portion to permit the insertion of meeting lateral corners on adjacent shingles under the lower corner of 85 said body portion with one side margin of each adjacent shingle engaged in one of said channels, the lower half of said body portion being pressed outwardly and forming a cavity between the body portion of the 90 shingle and the roof, substantially as described.

In testimony whereof I affix my signature in the presence of two witnesses.

HERMAN W. KOERNER.
